UNITED STATES PATENT OFFICE.

OLUF LEE, OF ROLETTE, NORTH DAKOTA.

COMBINATION-TOOL.

1,344,046.

Specification of Letters Patent. Patented June 22, 1920.

Application filed January 27, 1917. Serial No. 144,897.

To all whom it may concern:

Be it known that I, OLUF LEE, a citizen of the United States, residing at Rolette, in the county of Rolette, in the State of North Dakota, have invented certain new and useful Improvements in Combination-Tools, of which the following is a specification.

This invention relates to improvements in combination tools and its object is to provide 10 a tool-head adapted to interchangeably carry a plurality of tools. With the foregoing and other objects in view, the invention consists in the combination and arrangement of parts to be hereinafter fully described in 15 this specification, pointed out in the appended claim and illustrated in the accompanying drawings which form a part of the specification and in which—

Figure 1 is a side elevation, partly in 20 section to afford a better illustration, of the tool.

Fig. 2 is a section taken on line 2—2 of Fig. 3.

Figs. 3 and 4 are details of some of the 25 tools that may be used with the present head.

Figs. 5, 6, 7 and 8 illustrate other tools provided with shanks so formed as to be capable of operative engagement with the 30 present head.

Like reference characters denote corresponding parts throughout the several views.

The reference numeral 1 denotes the handle of the tool which is provided with the 35 hammer-like head 2 which is formed with a terminal socket 3 adapted to receive the shank 4 of any tool 5 which shank is threaded at 6 to engage with socket 3 the axis of which is disposed at substantially 40 right angles to the handle 1; the shank being engaged by the set-screw 7 that extends through a perforation in the socket 3. In Fig. 1 the socket 3 retains the shank 4 of a pick. In Fig. 3 wrench jaws are shown, 45 the handle of one of which may carry a leather punch 4^a. In Figs. 7 and 8 a saw blade is shown which is provided with a shank 4 by means of which the blade may be secured to the head 2. In Fig. 5 a nut 50 cracker or pincers is shown carried by the head 2, this tool being provided with an

auxiliary handle 5^a normally extending in parallel relation to the handle 1. The handles 1 and 5^a are manually pressed together to bring the jaws of the tool together upon the work. In Fig. 6 the shank is integral with a stationary jaw A to which the movable jaw B is pivoted at C, said jaw terminating in the handle D. The free end of the jaw A is beveled as at E and pointed as at F while the jaw B is recessed as at G and serrated. This tool is a combination nut cracker, pipe wrench and stamping tool. The work is retained between the free end of the jaw A and the serrated portion of the jaw B. The tool is operated by manually pressing the handles 1 and D together thus bringing the jaws A and B together upon the work. Small objects, such as small pieces of pipe and the like, may be gently held between these jaws, or by pressing them firmly together the imprint of the serrations of jaw B may be formed upon the work.

What is claimed is:—

A combination tool of the character described comprising a fixed handle, a head carried at one end of said fixed handle and having in one side thereof a threaded socket with its axis arranged at substantially right angles to the direction of length of the fixed handle, a fixed jaw, a threaded shank on the fixed jaw removably screwed into said threaded socket on the head, means passing through the head and entering said socket for engaging with the shank whereby to lock the latter from turning, a movable jaw co-operating with and pivoted on said fixed jaw, and a movable handle on the movable jaw extending substantially parallel with said fixed handle whereby said handles may be squeezed together in a single hand of the operator to swing said movable jaw closed against the fixed jaw.

In testimony that I claim the foregoing as my own I have hereto affixed my signature in the presence of two subscribing witnesses.

OLUF LEE.
